UNITED STATES PATENT OFFICE.

JOHN J. BRIDGEFORD, OF PHILADELPHIA, PENNSYLVANIA.

STEAM-BOILER FURNACE.

Application filed June 1, 1921. Serial No. 474,116.

To all whom it may concern:

Be it known that I, JOHN J. BRIDGEFORD, a citizen of the United States, residing at Philadelphia, in the county of Philadelphia 5 and State of Pennsylvania, have invented certain new and useful Improvements in Steam-Boiler Furnaces, of which the following is a specification.

My invention relates to steam-boiler furnaces and particularly to means for obtaining a more perfect combustion of the fuel with a consequent elimination of smoke and unspent gaseous products of combustion.

Prior constructions have been devised for 15 supplying air to the fire above the grate-bars in order to furnish oxygen in sufficient quantities for perfect combustion. In such prior constructions flues have been provided in the side walls consisting of tiles placed 20 end-to-end, such flues communicating with intake flues in the bridge wall whereby to heat the air delivered above the fire.

The purpose of the present invention is to generally improve such prior constructions, one object of the invention being to 25 provide a novel type of flue for the side walls.

Another object of the invention is to provide means by which an attendant may regulate at will the supply of air.

A further object of the invention is to so 35 construct the bridge-wall that it will act as baffle wall and not only cause an even distribution of the heat around the crown sheet of the boiler but also a strong suction or draft to thoroughly mix the air drawn over the fire through the flues in the side walls with the gases of combustion whereby to secure a complete burning of such gases before 40 passing over the bridge-wall.

A still further object of the invention is to provide a construction for the carrying out of the above objects which can be applied to boilers already set as well as to new 45 boilers in the setting.

These and such other objects as may hereinafter appear are attained by the novel construction, combination and arrangement of parts to be hereinafter specifically described 50 and claimed.

Reference will now be had to the accompanying drawings forming a part of this specification, wherein:

Figure 1 is a horizontal sectional view of 55 my improved furnace construction taken

just below the boiler and looking downwardly.

Figure 2 is a vertical sectional view of the furnace construction showing the boiler in elevation.

Figure 3 is a vertical sectional view taken on the line 3-3 of Figure 1 looking in the direction of the arrows.

Figures 4, 5 and 6 are detail views of a fire brick block for the formation of the flues.

Throughout the following detailed description and on the several figures of the drawing, similar parts are referred to by like reference characters.

Referring to the drawings, A designates a steam boiler and 1 and 2 the side walls and 3 the bridge-wall of the furnace. The grate-bars are designated by the reference numeral 4 and 5 designates the ash-pit.

The flues 6 are arranged in the side walls 75 above the grate-bars and are formed of fire brick blocks 7 placed end-to-end and constructed to interlock. Each block is 12 inches long, $8\frac{1}{2}$ inches thick, and 5 inches high.

Extending longitudinally through the center of each block is a 2 inch hole and communicating therewith are four transverse $\frac{1}{2}$ inch holes extending to one edge face of the block. The two end $\frac{1}{2}$ inch holes are $1\frac{1}{2}$ inches from the respective 85 ends of the block while 3 inches separates the intermediate holes from each other and from the end holes so that when a series of blocks are arranged end-to-end a flue will be formed having a 2 inch passage 90

extending longitudinally thereof from end-to-end and having transverse $\frac{1}{2}$ inch holes spaced uniformly 3 inches apart and extending from one edge face of the flue to and communicating with the central longitudinal 95

2 inch passage. Each block is formed at one end with a slight protuberance 8 surrounding the longitudinal 2 inch hole while at the other end of the block a corresponding recess 9 is formed. When the blocks are placed 100

end-to-end the protuberance 8 of one block will interlock in a recess 9 of the next block and form a tight joint so that the air drawn 105 into the flue through the longitudinal 2 inch passage can only escape through the transverse $\frac{1}{2}$ inch holes. The blocks 7 are of such

size as to take the exact space of two courses of ordinary brick both in width and height which greatly facilitates the installation of 110

the flues in the side walls during the con-

struction of new furnaces as well as in furnaces already built and the flues can be renewed without unnecessary molestation of the outer walls. Also due to the size of the 5 blocks the longitudinal 2 inch passage and the transverse $\frac{1}{2}$ inch holes do not appreciably weaken the construction of the side walls for either the fire brick lining or the red brick filling as it has a $\frac{3}{4}$ inch bearing 10 surface each side of the 2 inch passage.

The flues 6 communicate at one end with vertical flues 10 formed in the side walls. Extending through the bridge-wall just beneath the grate-bars and centrally of the 15 side walls and projecting slightly at one end into the ash-pit is a 6 inch pipe 11. The pipe 11 projects at its other end slightly to the rear of the bridge-wall and has connected thereto a 6 inch T 12. A pair of 6 20 inch pipes 13 extending transversely of the furnace and parallel to the rear face of the bridge-wall and are joined at one end to the T 12 and at the other end to 6 inch elbows 14 set into the side walls and communicating 25 with the vertical flues 10.

The end of the pipe 11 which projects into the ash-pit has hinged thereto a damper 15 which is controlled by means of a rod 16 having one end connected to the 30 damper and which passes through the cast iron front between the ash-pit doors. The rod 16 is provided at its outer end with a rack 17 for cooperation with an edge of the cast iron front to hold the damper in adjusted 35 positions. The damper and damper rod are so constructed and arranged as not to interfere with the manipulation of the grate-bars nor the cleaning of the ash-pit. By means of the damper 15 the amount of 40 oxygen can be regulated for the burning of either soft or hard coal and also for oil burning systems.

A 9 inch fire brick wall 18 extends upwardly from the floor of the combustion 45 chamber and has a top wall 19 joining the bridge-wall to form a compartment 20 to encase and form a superheating chamber for the intake pipes 13. The air taken into the pipe 11 from the ash-pit is thus superheated in the compartment 20 as it passes 50 through the pipes 13 before being delivered to the flues 6 to be drawn through the transverse holes therein over the fire. The provision of the wall 18 also allows for the 55 cleaning of the combustion chamber without any obstruction.

On top of the bridge-wall is built a 9 inch fire brick wall 21 forming an extension of the bridge-wall. The upper edge of the bridge-wall extension 21 has a curved formation similar to that of the crown sheet of the boiler and extends to within 7 inches of the crown sheet in order to provide for an even distribution of the heat around the 60 crown sheet. The wall 21 also forms a baffle 65

compelling the hot gases of combustion to rise and pass through the narrow space between the edge of the wall 21 and the crown sheet in order to pass to the combustion chamber, thus creating a strong suction or 70 draft in the chamber above the grate to draw in the air from the flues 6 to commingle with the gases of combustion to cause a complete burning of the same with a consequent elimination of smoke and unspent gases and preventing the formation 75 of clinkers.

Having thus described my invention, what I claim as new and desire to secure by Letters Patent of the United States is:

1. In a furnace having side walls, a bridge wall and grate in front of the bridge wall, said bridge wall including a forward extension inclining upwardly from the level of the grate and forming a deflecting surface for directing the gases of combustion toward the boiler, a wall on top of said bridge wall extending upwardly into close proximity to the crown sheet of the boiler and providing a narrow uniform passage 90 therebeneath toward which the deflecting surface aforesaid directs products of combustion, a wall rising from the floor of the combustion chamber in the rear of and spaced away from the bridge wall connecting at its top with the latter to form a super-heating chamber, an air conduit extending from the ash pit through the bridge wall into the super-heating chamber and having lateral branches therein, and a flue 95 extending longitudinally of each side wall above the grate and communicating at regularly spaced intervals with the space above the same, said flue joining the lateral branches aforesaid.

2. In a furnace having side walls, a bridge wall and grate in front of the bridge wall, said bridge wall including a forward extension inclining upwardly from the level of the grate and forming a deflecting surface for directing the gases of combustion toward the boiler, a wall on top of said bridge wall extending upwardly into close proximity to the crown sheet of the boiler and providing a narrow uniform passage 100 therebeneath toward which the deflecting surface aforesaid directs products of combustion, a wall rising from the floor of the combustion chamber in the rear of and spaced away from the bridge wall connecting at its top with the latter to form a superheating chamber, an air conduit extending from the ash pit through the bridge wall into the super-heating chamber and having lateral branches therein, a flue 105 extending longitudinally of each side wall above the grate and composed of a series of fire brick blocks set into the wall, said blocks having a relatively large longitudinal passage extending from end to end of 110

115

120

125

130

the series centrally of the blocks with a series of uniformly spaced relatively fine openings extending transversely of the series, said blocks each having at one end 5 an annular recess and at the other end an annular projection surrounding the longitudinal passage and forming a substantially air tight joint, and damper means arranged at the inlet of the intake conduit having manipulating means therefor extending to 10 the front of the furnace.

In testimony whereof I affix my signature.

JOHN J. BRIDGEFORD.
